ATTORNEY

UNITED STATES PATENT OFFICE.

THOMAS BURKE, OF NEW YORK, N. Y.

SAFETY-VALVE.

SPECIFICATION forming part of Letters Patent No. 315,475, dated April 14, 1885.

Application filed May 9, 1884. (No model.)

To all whom it may concern:

Be it known that I, THOMAS BURKE, of the city, county, and State of New York, have invented certain new and useful Improvements 5 in Safety-Valves for Kitchen-Boilers and Heaters of Various Kinds, of which the following is a full, clear, and exact description, reference being had to the accompanying drawings, forming a part thereof.

10 The object of my invention is to provide a simple and easily-adjusted valve to prevent the explosion of kitchen-boilers especially. This valve is so constructed and arranged that it can be readily attached to any kind of a kitchen-boiler or other receptacle where steam is accumulated or generated.

15 The advantages possessed by my invention over any that have preceded it for the purpose stated are many.

20 In all the steam-valves of this class now known or in use the spring which exerts the pressure on the valve is confined in the same box with the valve, and the spring, being thus exposed to the action of the steam, soon loses 25 its elasticity and ceases to exert the required degree of resistance on the valve.

In my invention the spring is placed at a distance from the valve-box by and constructed with the valve by a piston-rod.

30 Figure 1 is a sectional view of the valve, showing the cylinder or tube, the valve, piston, spring, and adjusting-cap. Fig. 2 shows a transverse section of the piston and valve-box. Fig. 3 is a transverse sectional view of 35 the valve and valve-box with the discharge-pipe. Fig. 4 represents the piston rod and valve, and Fig. 5 represents the spring.

In the drawings, A is a cylinder or tube,

being of uniform size and diameter. In this there is inserted a piston-rod, C. At the lower end of this piston-rod there is attached a valve, E, the upper part of which, E, is made of metal, and the lower part, f, of leather or other flexible substance. This valve E operates in the box G. In the upper chamber of 45 the tube A, and on the piston C, I have arranged a spiral spring, D. This spring is held down and its pressure on the piston C regulated by the adjusting-cap B. The valve thus constructed and arranged can be attached 50 by the screw F to a pipe, J, on any boiler or steam-receptacle, and the resistance on the valve may be easily regulated by the adjusting-cap B. The steam in the boiler exerts the pressure on the valve E, and when the pressure reaches a given point the valve is forced 55 upward and the steam or gas escapes through the pipe I.

Having thus described my invention, what I claim is—

60 In a safety-valve for kitchen boilers and heaters, the combination, with a metallic tube, A, of a piston, C, which fits closely in said tube, and provided at the lower end with a valve-disk which operates in a valve-box, a 65 pressure-spring inserted between the screw-cap B and the upper end of said piston, an adjusting-cap, B, adapted to regulate the pressure on the piston-valve, and the valve-box G, all combined and arranged substantially as and for the purpose set forth.

THOMAS BURKE.
